WILLIAM R. F. PATCHETT, OF BOLTON, ENGLAND, ASSIGNOR OF ONE-THIRD TO JOHN T. BOOTH, OF LEEDS, ENGLAND.

INTERNAL-COMBUSTION ENGINE.

1,250,346.

Specification of Letters Patent. Patented Dec. 18, 1917.

Application filed June 4, 1914. Serial No. 842,819.

To all whom it may concern:

Be it known that I, WILLIAM R. F. PATCHETT, a subject of the King of England, residing at Bolton, Lancashire, England, have 5 invented a certain new and useful Improvement in Internal-Combustion Engines, and declare the following to be a full, clear, and exact description of the same, such as will enable others skilled in the art to which it 10 pertains to make and use the same, reference being had to the accompanying drawings, which form a part of this specification.

This invention relates to internal combustion engines of the two cycle type, and an 15 object of the invention is an engine of the type stated having a higher efficiency and a greater range of variation in operation than has commonly heretofore attained. I accomplish this and other objects through 20 providing a working unit of two cylinders having pistons connected in opposite relation to a single crank shaft and the fresh, explosive, gases are admitted alternately to the explosion chambers of the cylinders 25 through a common valve rotatably mounted in proper relation therewith and so constructed and arranged as to operate at comparatively slow speed and without overheating. The pistons are of the stepped 30 type, the lower larger one of which provides the compressed charge for the working piston of the opposite cylinder and vice versa.

With the usual explosion engines utilizing a rotatable valve for controlling the flow of 35 gases to and from the working chamber, great difficulty has been encountered in properly lubricating the valve and also in preventing the overheating thereof. The present invention seeks to overcome these 40 difficulties and furthermore to provide a clean explosive mixture at the point of ignition. In the ordinary two cycle engine the cylinders are oftentimes not properly cleared of burnt gases and upon the succeeding 45 compression stroke such burnt gases are mixed with the inflowing compressed charge resulting in a mixture that is not readily ignited by an electric spark. In the engine herein disclosed the compressed charge is introduced into the upper end of the cylinder 50 at the proper time and flows downward therethrough forcing the burnt gases out at the bottom and, upon the compression stroke, the fresh gas is pocketed about the sparking

terminals resulting in proper firing of the 55 charge. In conjunction with such proper scavenging of the working cylinder and provision of clean explosive mixture, the valve employed provides a chamber in which the large compression piston of one cylinder 60 forces a fresh mixture on its up-stroke, the capacity of the valve and of the conduits leading thereto from the compression cylinder determining the extent of the compression of the gas prior to its introduction 65 into the explosion chamber of the opposite cylinder. By this arrangement the compression stroke of the working cylinder may be made to compress the gas to any desired degree depending of course upon the degree of 70 its compression prior to its introduction into the explosion chamber, and although the hollow rotary valve herein disclosed is not adjustable in capacity, the extent of prior compression desired may be readily determined 75 mathematically, or by experiment as the designer may prefer. These and various other objects and novel features of construction are hereinafter more fully described and claimed and shown in the accompanying 80 drawings in which—

Figure 1 is a side elevation of an engine embodying my invention.

Fig. 2 is a vertical section showing the two cylinders, one of which is sectioned on the 85 center line of the cylinder showing the cylinder port in the head thereof and the other one of which is shown substantially on a line $w-w-y-y-z$ of Fig. 1, showing clearly the bypass from the compression cylinder leading 90 into the rotary valve.

Fig. 3 is an elevation of the rotary valve.

Fig. 4 is an elevation of one end thereof.

Fig. 5 is an elevation in the opposite end thereof.

Fig. 6 is a longitudinal section of the valve.

Fig. 7 shows a section of the valve on line $w-w$ of Fig. 6, showing the relation of the ports to the bypasses of the two cylinders 100 controlled by the compression pistons.

Fig. 8 is a section through the valve on line $y-y$ of Fig. 6 showing the relation of the ports in the plane of said section to the passages leading into the explosion chamber 105 of the two cylinders.

Similar characters refer to similar parts throughout the drawings and specification.

As heretofore stated two cylinders are required to form a working unit as shown at 1 and 2 in Fig. 2. As clearly shown in said figures, the cylinder 1 has a chamber 3 for the piston 4 and a chamber 5 for the piston 6 formed integrally with the piston 4. The cylinder 2 is likewise formed and provided with a working piston 7 and a compression piston 8. The explosion chambers are properly water-jacketed as may be seen in Fig. 2 to prevent overheating of the walls thereof and the upper end of the explosion chamber is formed in the detachable head 9. The head however may be formed integrally with the cylinder casting if so desired. The upper end of the explosion chamber is substantially cone-shaped and leading from the apex thereof is a passageway 10 opening through the wall 11 of the chamber in which the rotary valve 12 is positioned and providing an inlet port 13. Both cylinders are provided with similar ports as may be seen clearly in Fig. 8. The rotary valve 12 is provided with a series of ports 14 adapted to register successively with the ports 13 and 13^a of the explosion chambers of the two cylinders, the ports in the valve being so positioned that when a port 14 is open to one of the cylinder ports, the other cylinder port is closed. Each cylinder is provided with a passageway 15 or 15^a opening into the compression chamber controlled by the large piston 6 or 8. The relation of the two passages 15 and 15^a to the rotary valve is shown clearly in Fig. 7 where it may be seen that when one of the ports 16 of the valve is open to the passageway 15, the other passage 15^a is closed thereto but is open to a port having a different function as hereinafter described. The passageways 15 and 15^a open into the valve chamber at one end thereof while the ports 13 and 13^a of the explosion chambers open into the said valve chamber at the other end thereof. The ports 14 in the valve register with said cylinder ports while the ports 16 and 17 alternately register with the passageways 15 and 15^a.

The valve 12 has a flange 18 upon one end thereof adapted to ride in a socket provided in the engine head, and the opposite end is provided with a shaft 19 having a key 20 adapted to engage in a slot provided in the closed end of the valve. Said key and slot, as shown in Fig. 4, are formed at one side of the center of the shaft and valve which is desirable in order that, in dismounting and resetting the valve, it must necessarily be turned to correct position relative to the position of the operating gears and consequently to the pistons. As shown in Fig. 2 a bevel gear 20^a is secured to the projecting end of the shaft 19 and meshing therewith is a bevel gear 21 on a vertical shaft 22, said gears being inclosed in a pocket 23 in the engine head which is provided with a cover

plate 24. The shaft 22 terminates in a radially grooved or serrated head 25 adapted to engage a similarly formed head 26 on the vertical shaft 27 in longitudinal alinement with the shaft 22. A coupling nut 28 is provided to engage over the threaded face of the head 26 of the shaft 27 to bind the two serrated faces of the heads 25 and 26 in position. To alter the timing of the valve, said coupling nut 28 is loosened and one or the other of said shafts rotated to the right or left and again brought into engagement and secured in place by the coupling whereupon the valve opens and closes either earlier or later as may be necessary to produce the desired result. As shown more clearly by dotted lines in Fig. 1, the shaft 27 terminates in a bevel gear 29 meshing with a like gear 30 on the horizontally positioned shaft 31 that may be conveniently mounted in bearings 35 provided on the crank case. On the shaft 31 is a spur gear 32 meshing with a spur gear 33 on the crank shaft 34 of the engine. The relation of the gear train above described is such that the valve 12 rotates at one-third the speed of the crank shaft 34, such slow speed being possible by reason of the porting of the valve and the wall engaged thereby as heretofore mentioned.

As shown in Fig. 1, the gears 32 and 33 may be provided with an inclosing casing 35 and in the said view is shown a casing 36 that may be provided to inclose the driving chain or belt for operating a force feed oiler, the outline of which is shown by dotted lines 37. As oiling devices are common in this art in which means are employed to force oil to the parts that are desired to be lubricated, further description thereof is deemed unnecessary it being understood that tubes 38 may be employed to carry the oil to such parts as require lubrication, as for instance, to the channel 39 in the engine head leading to and terminating in the wall of the valve chamber, and by means of which the valve may be properly lubricated.

The peculiar structure of the valve and the relation of the ports one to another and to the ports in the walls of the valve chamber are shown clearly in Figs. 3 to 8 inclusive. In what may be termed the intake end of the valve, there are six ports in the circumferential wall thereof, three of which are similar to the port 16 and three of which are similar to the port 17, as shown in section in Fig. 6. Each of the ports 16 connects with the inlet channel 40 centrally in the end of the valve with which the intake manifold 41 registers. To this manifold 41 is secured a carburetor of any approved form. As may be seen in Fig. 7, when one of the ports 16 is in registration with the port of the bypass or conduit 15, one of the ports 17 is in registration with the bypass 15^a of the other cylinder. As may be seen in Fig. 6, the

ports 17 lead into the interior of the valve body and communicate with the ports 14 therein which register alternately with the ports 13 and 13^a of the explosion chambers.

The operation of the engine is as follows: Let it be supposed that the pistons 7 and 8 of the cylinder 2 are on the power-stroke, while the pistons 4 and 6 of cylinder 1 are on the upstroke. During the down stroke, ordinarily caused by an explosion of gas in the explosion chamber of cylinder 2, one of the ports 16 of the valve registers with the bypass 15. The downward movement of the piston 8 in the compression chamber of said cylinder 2 draws a charge from the carbureter channel 40 through one of the ports 16 and the bypass 15 into the chamber surrounding the piston 7. Prior to the piston reaching the bottom of its stroke the valve has rotated sufficiently for the said port 16 to be closed to the bypass 15, and as the piston starts on its upstroke, one of the ports 17 registers with the bypass 15, and the charge in the compression chamber controlled by the piston 8 is forced through the port 17 into the hollow body of the valve. It is to be noted that this fuel charge is cold and being brought into the interior of the valve aids in maintaining the valve at low temperature. As the port 16 passes out of registration with the port of the bypass 15 and as the working piston of the opposite cylinder reaches the bottom of its downward stroke, one of the ports 14 registers with the port 13 in the upper end of the cylinder casing 1, and this compressed charge in the valve body flows into the upper end of the explosion chamber of the cylinder 1, forcing the gases therein out through the exhaust port 45 leading to the exhaust manifold 46 common to both cylinders. As the said port 14 passes out of registration with the port 13, the piston 4 begins its up-stroke in which the fresh charge introduced thereinto is further compressed, the purest gas being in the upper end of the explosion chamber in the passageway 10 in the upper end of which is located a spark plug 47. During this upward compression stroke of the pistons 4 and 6 a charge is forced through the bypass 15^a into the hollow interior of the valve for use in cylinder 1. As the piston 4 reaches the uppermost part of its stroke, or at such other period as may be determined by a commutator or the like, a spark is produced by means of the usual devices for this purpose and the charge in the cylinder 1 is exploded, forcing the piston 4 downward on its working stroke, during which movement the piston 6 draws fresh gas into the compression chamber.

It is thus to be seen that the pistons operate in alternate relation in the respective cylinders and that one prepares and compresses the explosive charge for use in the

other cylinder, the fuel charge being properly distributed or delivered through operation of the rotatable valve 12.

As heretofore stated there are three ports of each kind described in the valve body so that each bypass and compression chamber as well as the explosion chamber is opened to the valve at each third of a revolution thereof, the ports being properly relatively spaced circumferentially about the valve. Therefore, the valve may rotate very slowly. It is also to be noted that the valve may be set so that the ports may open and close either early or late relative to the piston position by means of the coupling 28 heretofore described but the relative position of the valve ports one to another may not be altered. By providing an exhaust port controlled by the working piston, the hot burned gases do not pass through the rotatable valve and, therefore, said valve may be readily kept cool.

By using a valve of the type described to control the flow of gas alternately to the compression chambers and properly distribute the charge alternately to the explosion chambers of the two cylinders, the efficiency of the engine approximates that of the usual four-cycle type, as the bypass 15 or 15^a leading to the respective compression chamber may be opened to the carbureter and fuel drawn therethrough for practically the entire working stroke of the piston, which is contrary to the action of the ordinary two-cycle engine in which the inlet port is opened for but a very small part of the piston stroke. Also by delivering the fuel charge into the upper end of the explosion chamber the burned gases are actually forced out of the exhaust port by the inflowing charge.

The preferable setting of the valve relative to the bypass ports is such that the said ports are opened about 15 degrees over the upper dead center and closed 35 to 45 degrees late, or beyond the bottom dead center. By such arrangement the compression chamber is sure of obtaining a complete and full charge under all speeds of operation. The ports 14 are so positioned as to open just after the piston passes the upper edge of the exhaust port and the burned gases begin to flow therethrough, said ports being open until the exhaust port is again closed on the return stroke of the said piston. It will be noted that by this arrangement the said port leading into the explosion chamber is opened before the piston therein has reached the bottom of its stroke and before the piston in the companion cylinder has reached the uppermost point of its stroke. Therefore, the gas in the hollow interior of the valve, which has been put into a state of compression prior to the opening of the explosion chamber, is impelled, after the opening of the said port, by the ascending piston

of the companion cylinder thus forcibly ejecting the burned gases in the explosion chamber under consideration.

As is shown in Fig. 3, expanding rings 5 50, 51 and 52 are preferably employed for preventing a leakage of gas from a port 14 along the surface of the valve body to a port 16 or 17. As is also shown in said figure, the surface of the valve near the ports may 10 be grooved longitudinally as at 53 or 54, with very fine grooves. The purpose of these grooves is to retain oil and not only properly lubricate the interior surface of the valve chamber, but also serve to oil- 15 pack each of the said ports and prevent gas passing circumferentially about the valve from one port to another. These grooves are supplied with oil through a channel 38 and other channels leading into the valve 20 chamber, preferably at points contacted by the valve rings, which by reason of their expansion prevent a too rapid flow of oil into the chamber. By such provision of packing rings and oil grooves the valve body may be 25 made to comparatively loosely fit in the valve chamber whereby whatever expansion is caused by heating of the valve does not make the said valve stick in the chamber, and the valve will operate equally as well 30 when the engine is cold at the time of starting as at a later period when the parts have become heated and tightly fit the inclosing wall.

The size of the interior of the rotatable 35 valve determines largely the extent to which the charge is compressed prior to delivery to the explosion chamber of either cylinder, and the charge may be compressed to considerably higher degree in the engine herein 40 disclosed, than in any engine of the two cycle type with which I am familiar. As the engine is therefore, somewhat difficult to turn over by operation of the crank 60, I have provided relief valve 61 about mid- 45 way of the length of the explosion chamber of both cylinders which may be opened at the time it is desired to start the engine. By such arrangement the working pistons only compress the charge remaining above 50 the port 62 leading to the relief valve. As soon as the engine starts to operate the valves 61 may be closed whereupon the engine will compress the charge to a greater degree prior to ignition.

55 Having thus briefly described my invention and its mode of operation, what I claim and desire to secure by Letters Patent of the United States is—

1. An internal combustion engine of the 60 two cycle type comprising, as a working unit, a pair of cylinders each provided with a compression chamber and an explosion chamber, pistons in said cylinders arranged to operate in alternate relation and fitting 65 both of said chambers, a valve chamber mid-

way between the cylinders at the upper end thereof, passageways leading from the heads of the explosion chambers to corresponding ports on opposite sides of the valve chamber, passageways leading from the compression chambers to similar ports in opposite sides of the said valve chamber, a hollow cylindrical valve in said chamber having a port adapted to register successively with the ports in communication with the explosion chambers and also having a port adapted to register successively with the ports in communication with the compression chambers, the valve ports being so relatively positioned that when one port is opened to the 70 compression chamber of one cylinder the other port is opened to the explosion chamber of the other cylinder, the said valve ports being in communication through the hollow interior of the valve, said valve also 75 having a port adapted to register with the ports in communication with the compression chambers and in alternate relation with the other port so adapted to register, said last named port being continuously in communication with a charge forming device 80 and closed to the interior of the valve.

2. An internal combustion engine of the two cycle type comprising a pair of cylinders each provided with a compression chamber and an explosion chamber, pistons arranged to operate in alternate relation and each fitting both of said chambers in its 85 respective cylinder, the compression chamber of one cylinder being adapted to produce an explosive charge for the explosion chamber of the other cylinder, each of said cylinders having an inlet port in the upper end of the explosion chamber and an exhaust port near the lower end thereof, a 90 valve chamber substantially midway between the cylinders at the upper end thereof having ports in the wall each in communication with the explosion chamber of a single cylinder, and other ports each communicating with the compression chamber of a single cylinder, a hollow cylindrical valve 95 adapted to be rotated in said chamber in timed relation with the piston movement, said valve having a plurality of ports adapted to register successively with the ports in communication with the explosion chambers, and a second series of ports adapted to successively register with the ports in communication with the compression chambers, said 100 first and second series of valve ports being in communication through the interior of the valve, said valve also being provided with a third series of ports alternating with the said second series and adapted to successively register with the ports in communication with the compression chambers, said last named ports each being in communication with a charge forming device and closed to the interior of the valve.

3. An internal combustion engine of the two cycle type comprising a pair of cylinders each having an explosion chamber and a compression chamber, pistons for said 5 cylinders adapted to reciprocate therein in alternate relation, a valve chamber, passageways leading from the heads of the explosion chambers to corresponding ports on opposite sides of the valve chamber, passageways leading 10 from the compression chambers to similar ports in opposite sides of the said valve chamber, a hollow cylindrical valve in said chamber having a port adapted to register successively with the ports in communication 15 with the explosion chambers and also having a port adapted to register successively with the ports in communication with the compression chambers, the valve ports being so relatively positioned that when one port is 20 opened to one of the compression chambers the other valve port is opened to the explosion chamber of the other cylinder, the said valve ports being in communication through the hollow interior of the valve, said valve 25 also having a port adapted to register with the ports in communication with the compression chamber and in alternate relation with the other valve port so adapted to register, said last named port being continuously 30 in communication with a charge forming device and closed to the interior of the valve.
4. An internal combustion engine of the two cycle type comprising, as a working unit, a pair of cylinders each having a compression chamber and an explosion chamber, pistons in said cylinders adapted to 35 operate in alternate relation, each explosion chamber having an exhaust port controlled by the piston therein, a cylindrical valve
- chamber, passageways leading from the 40 heads of the explosion chambers to corresponding ports on opposite sides of the valve chamber, passageways leading from the compression chambers to similar ports on opposite sides of the valve chamber 45 longitudinally spaced from said first named chamber ports, a hollow cylindrical valve in said chamber, means for rotating said valve in timed relation with the piston movement, said valve having a plurality of ports there- 50 in adapted to register successively with the ports in communication with the explosion chambers and also having a plurality of ports adapted to register successively with the ports in communication with the compression chambers, the said valve ports being 55 so relatively positioned that when a port of one series is opened to the compression chamber of one cylinder, a port of the other series is opened to the explosion chamber 60 of the other cylinder, the said sets of valve ports being continuously in communication through the hollow interior of the valve, said valve also having a plurality of ports adapted to register successively with the 65 valve chamber ports in communication with the compression chambers and in alternate relation with the other series so adapted to register, said third series of ports being in 70 communication with a charge forming device and closed to the interior of the valve.

In testimony whereof, I sign this specification in the presence of two witnesses.

WILLIAM R. F. PATCHETT.
